ford, and John H. Staib, Scotch Plains, N. J.

Application November 16, 1951, Serial No. 256,662

9 Claims. (Cl. 73—422)

1

This invention relates to sample cutters such as are employed in connection with research laboratory apparatus for fractional distillation of hydrocarbon fuels for the purpose of taking therefrom test samples of the distillate at intervals controlled by time, volume of fraction, or temperature change.

As is well known to persons skilled in the above-cited art to which the invention is particularly applicable, liquid hydrocarbon fuel is raised to the boiling point in a still pot located at the base of a vertical distillation column. Vapor from the boiling liquid rises in the column to varying heights, condenses into the liquid state, and flows back into the still pot. The most volatile components, i. e. those having the lowest boiling point, concentrate at the top of the column and it is these fractions from which it is most desirable to obtain cuts for test purposes, so a cooling jacket is provided surrounding the top portion of the distillation column to accelerate condensation at this point. At predetermined intervals, distillate from the top portion of the column is diverted into an exteriorly located collector, which also has a cooling jacket. In order to lower the temperature at which the liquid contents of the still pot will boil and thereby insure safe distillation without danger of cracking or burning, the pressure in the apparatus is reduced to a suitable degree below that of atmospheric distillation by use of a vacuum pump. When in the operation of the apparatus a sufficient volume of distillate has accumulated in the collector, it is drawn off through a valve-controlled drainage duct into a sample tube or receiver.

Prior to the present invention, it has been the usual practice to take periodic cuts by manual operation of the drainage duct valve and segregation of the samples in separate, readily identifiable receivers. We are also aware of a sample cutter invented by another which is automatic in operation. That device has a rotatable frame or rack which holds a great many vertically disposed sample tubes that are arranged in concentric circular rows. A filling tube connected with the drainage duct of the distillation apparatus is swingable on a vertical axis so that its lower discharge end may overlie each receiver of the series in turn as the rack is intermittently rotated. After all receivers of one row are filled, a cam plate swings the discharge end of the filling tube over to the next row. This operation continues until the last empty receiver has been filled, whereupon the filling tube is displaced into registration with a discharge opening in the rack

and the motion of the latter is stopped. This automatic sample cutter was devised to reduce manual control to a minimum and even to permit unattended operation at night or on week-ends. It has numerous defects, however, among which the most serious are: (1) there is no control of the flow of distillate into or through the filling tube, so there will be spilling of liquid during the interval when the rack moves to bring a fresh sample receiver into registration with said tube; (2) all sample receivers are open to the atmosphere, so wasteful and dangerous evaporation of inflammable material will occur, which is particularly serious during those long periods when the device is unattended; (3) there is no provision for restoration of the associated distillation column to total reflux condition upon cessation of operation of the sample cutter; and, (4) the device cannot be made to operate successfully with distillation apparatus which has its internal pressure reduced below that of atmospheric distillation, for the distillate will not flow from the collector into the filling tube of the sample cutter.

With the above-enumerated defects of the prior art apparatus in mind, it is our primary object to provide an improved automatic sample cutter which shuts off the flow of distillate before each shift of the filling tube or conduit from one sample receiver to the next one in the series, which restores the distillation apparatus to total reflux condition and suspends all operation of the moving parts of the sample cutter immediately following delivery of a sample cut into the final receiver of the series, and which seals the sample receivers from the atmosphere either after receiving their samples in one embodiment of the invention or continuously in another embodiment.

Another object of the invention is to provide means by which an operator may interpose irregular manual operation of the filling conduit shifting means and the control valve of the distillation apparatus to permit the taking of a casual sample cut under unusual circumstances.

Further objects and advantages of the invention should become apparent as the following specific description is read in conjunction with the accompanying drawings, in which:

Fig. 1 is a small-scale diagrammatic view, partly in section, of a typical fractional distillation apparatus of the reduced-pressure or vacuum type, showing the preferred form of automatic sample cutter applied thereto; Fig. 2 is an enlarged perspective view, partly broken away, of the preferred form of automatic sample cutter

alone; and Fig. 3 is a fragmentary detail view, partly in section, of a sample receiver holder with a receiver in applied position, showing modification of the holder to add a manually operable cut-off valve.

Fig. 4 is a wiring diagram of the preferred means for operating the preferred form of sample cutter in connection with a fractional distillation apparatus of the type represented in Figs. 1 and 2, showing the condition of moving parts and circuits assumed when the device is shut-down automatically at the end of a major cycle of operation; Fig. 5 is a similar view, showing commencement of the first minor cycle of operation within a major cycle; Fig. 6 is a similar view, showing the next stage of operation of the first minor cycle; Fig. 7 is a similar view, showing a later stage of said first minor cycle; and Fig. 8 is a similar view, showing completion of the first minor cycle with the shut-down switch and total reflux restoration switch in broken line positions representing precise termination of a major cycle.

Fig. 9 is a plan view of a modified form of sample cutter, showing the filling conduit member at an intermediate position in the major cycle of operation; Fig. 10 is a fragmentary elevational view of the same, partly in section; and Fig. 11 is a detail exploded side elevation of a sample receiver and holder, the latter being broken away.

Before proceeding with description of the specific structural details of the invention, it should be made clear that the invention has other useful applications outside the art of fractional distillation of hydrocarbon fuels. In the various industrial arts, there are chemical processes and qualitative treatment of liquids and solids in granular or pulverulent form in the course of which the employment of an automatic sample cutter such as ours will fill a real need. In the accompanying drawings, the invention is represented in its adaptation to a typical distillation apparatus, but it will be understood that it is intended to cover all adaptations, changes and modifications of the examples of the invention herein chosen for the purpose of illustration which do not constitute departures from the spirit of the invention.

Because, in the adaptation of the invention to an apparatus for fractional distillation of hydrocarbon fuels, certain elements of the former enter into close cooperative relation with elements of the latter, conventional disclosure of a typical distillation apparatus has been included. In this connection, letters have been used to indicate old or standard elements, whereas numerals refer to that which is believed to be new.

Referring now to the drawings, in which like reference characters designate corresponding parts in the several views, Fig. 1 shows the typical distillation apparatus with the sample cutter mechanically and electrically connected thereto for operational use therewith. It will be observed that a vertical distillation column A communicates at its base with a still pot B. The upper end portion of column A is cooled by an external water jacket C. Column A and still pot B usually are made of glass and are integrally formed. Glass customarily is used for any other structural elements which may contain liquids which should be kept under visual observation. Immediately below water jacket C, there is flow diversion means comprising a fixed funnel D formed centrally in column A and a swinging

funnel E, which is pivotally mounted in column A close beneath funnel D to receive the descending flow of condensed vapor directed into it by said fixed funnel and which, when tilted into the position disclosed in Fig. 1, will divert the down-flowing distillate into a trough F that drains into a duct G leading exteriorly downward from column A into a collector H. Swinging funnel E may be made of glass but must include in its structure a suitable mass of magnetic material, such as iron, for cooperation with an exteriorly located electromagnet I which may be energized periodically by electric current through the medium of circuit J. The said circuit is controlled by a suitable timer T, which may be set to energize electromagnet I in accordance with a predetermined time ratio, such as for three seconds in every twenty seconds. When electromagnet I is energized, it draws the spout of swinging funnel E over into the position shown, wherein all descending distillate from fixed funnel D will be drawn off into collector H. When the circuit is broken at the end of the predetermined time period, swinging funnel E will gravitate into upright position wherein all distillate entering said funnel from then until electromagnet becomes energized again will be directed past trough F into the lower portion of column A for return to still pot B. This intermittent return, or reflux, of distillate from the top portion of column A is opposed to the total reflux condition which obtains when timer T is not in operation or circuit J is opened and swinging funnel becomes immobilized in its normal upright position.

Timer T is manually adjustable to vary the time ratio for diversion of distillate cuts into collector H. In addition to this normal control of distillate diversion, a secondary circuit 20 in series with circuit J is provided for connection with secondary control means which forms part of the electrical operating means of the preferred embodiment of our automatic sample cutter, which is shown in Figs. 1 to 8 inclusive, and will be described in detail presently.

Collector H, which usually is also provided with a cooling water jacket L, has a downwardly directed drainage duct M that may be controlled by a solenoid-actuated valve N. An extension drainage duct 22 leads from valve N downwardly for operative connection with the sample cutter in a manner which will be understood when details of the latter are described. In further adaptation of the distillation apparatus to cooperative combination with the automatic sample cutter, an operating electric circuit 22' for the coil of solenoid valve N is extended to said sample cutter for connection with the appropriate circuit of the electro-mechanical operating mechanism thereof.

It has already been mentioned that operation of the distillation apparatus can be carried out with comparative safety by reducing the internal pressure below that of atmospheric distillation. In order to obtain this condition, it is the usual practice to connect the upper end of distillation column A with a vacuum pump by a tubular main vacuum line O. Then, to equalize the pressure throughout the apparatus, a branch vacuum line P interconnects main line O and the upper end of collector H, and another branch line 23, having a manually operable shut-off valve 23a and a lower valve 23b controlling atmospheric vent 23c, extends from branch line P to the sample cutter for connection therewith in a manner and for reasons which will appear as the description progresses.

The preferred embodiment of the sample cutter, which is intended for use with distillation apparatus of the reduced-pressure type, is illustrated in Figs. 1, 2, 3, and 4 to 8, inclusive. The principal components of the device are: (1) the supporting structure 24; (2) the holding means 25 for sample receivers 26; (3) filling conduit member 27; (4) power transmission means 28 for producing relative motion between holders 25 and filling conduit member 27, which in this instance consists in rotating said member 27, the holders 25 being stationary; (5) envelope 29 to seal the interiors of sample receivers 26 and the various ducts and vessels of the distillation apparatus from the atmosphere; and (6) the electro-mechanical operating mechanism, preferably housed in supporting structure 24, which in mutual cooperative relation to the distillation apparatus motivates power transmission means 28 and coordinates its movement with the timed draining of sample cuts or fractions from the distillation apparatus and with the control of the swinging funnel E of the latter.

Supporting structure 24 may take any desired general form but preferably comprises a base 24a, standard 24b rising from said base, and horizontal arm 24c projecting from standard 24b. Standard 24b is box-like in structure for the purpose of housing the operating mechanism.

Sealing envelope 29 preferably is semi-spherical in form and has a top neck 31 which is removably secured in stationary position in supported relation to arm 24c of supporting structure 24 by any suitable means, such as by clamp 32. It is desirable to make envelope 29 of glass for reasons which should be obvious to those skilled in the art. The bottom wall of said envelope is up-thrust into exteriorly concave form as at 33 and merges with the side walls in an annular channel from which regularly spaced spout-form holders 25 for sample receivers 26 project downward. Holders 25 preferably are tapered toward their free ends to fit the mated flared necks 26' of receivers 26. Due to the glass composition of envelope and receivers, the mated abutting outer and inner surfaces, respectively, of holders 25 and receiver necks 26' may be ground in accordance with common practice to effect a fluid-tight joint. By providing downwardly raking hooks 34 on the necks 26' of receivers 26, it is convenient to apply closing pressure to said joint at each holder by means of a securing device 35, which may be in the form of the spring loop shown. Each securing device 35 is attached in suitable manner to envelope 29, as by integral perforate lug 36, and is adapted to be engaged with the hook 34 of any sample receiver 26 applied to the corresponding holder 25 after said securing device has been stretched into highly tensioned condition. The size and tension of the loop should be such that securing device 35 will exert a strong upward pull on the receiver. To facilitate manipulation of each securing device 35, it is preferred to provide a pendant flexible member 37, such as a chain, having a finger ring 38 at its free end.

When all holders 25 have sample receivers 26 operatively applied thereto, the bottom and side areas of envelope 29 will be hermetically sealed from the atmosphere. The top of envelope 29 must also be sealed from the atmosphere and the preferred means toward this end is the application of a cap 39, which may be made of glass and fits snugly in neck 31 of said envelope. The effectiveness of the sealed joint has been increased by making neck 31 outwardly flared in form and

by correspondingly tapering cap 39; also by providing ground mated surfaces. Incidentally, the reduced internal pressure will exert a tightening pull on cap 39 and also on receivers 26.

Cap 39 preferably is hollow and opens downwardly into the interior of envelope 29. In order to admit distillate samples from the valve-controlled drainage duct M of collector H of the distillation apparatus, extension duct 22, which leads downward therefrom, has been joined hermetically to the top wall of cap 39 in such a manner that it projects into the interior of said cap to a point slightly eccentric to the axis of the latter to form a delivery spout 40. Branch line 23 of vacuum line O of the distillation apparatus also is hermetically joined to the top wall of cap 39 in communication with the interior of envelope 29 to insure complete equalization of pressure between said envelope of the sample cutter and the interior of said distillation apparatus. This pressure equalization is necessary to permit flow of distillate from collector H into envelope 29 through drainage duct M, valve N, and extension duct 22.

Filling conduit member 27 is entirely located in the sealed interior of envelope 29 and cap 39 and is of such shape and size that it may be inserted freely through neck 31 at the time of assembly. By means to be described presently, filling conduit member 27 is mounted inside envelope 29 to rotate on a vertical axis concentric to the circular row of receiver holders 25. In construction, filling conduit member 27 preferably includes a funnel-shaped upper portion 41 having a mouth of such diameter that it underlies the spout 40 of drainage duct 22. A conduit 42 leads radially outward and downward from funnel portion 41 to a discharge spout 43 which overhangs the circular row of holders 25. While filling conduit member 27 may be pivotally mounted in various ways, it is preferred to employ the vertically aligned upper and lower pintles 44 and 45, respectively, which project axially from said member 27 and are journaled in bearings 46 and 47 provided respectively in the top wall of cap 39 and the bottom wall 33 of envelope 29.

The advantage of locating filling conduit member 27 and its pivotal bearings entirely inside sealed envelope 29 is that there are no externally exposed bearing faces to permit air from the atmosphere to leak into the envelope and thereby upset the carefully established pressure condition of the combined fluid chambers and passages.

The receiver holders 25 may be modified in construction as shown in Fig. 3 to provide a manually operable cut-off valve 48 for each holder in order that, whenever it is desired to detach some particular sample receiver while the sample cutter is in operation, the holder to which said receiver is attached may be closed to the atmosphere prior to such detachment. In this manner, the reduced-pressure condition of envelope 29 may be preserved.

Due to the sealed-in condition of filling conduit member 27, propulsion of said member is effected by magnetic attraction in penetration of the bottom wall 33 of envelope 29. Magnetic means, which may be a permanent magnet 49, is affixed to the underside of filling conduit member 27 adjacent to discharge spout 43 and is of such form that its under face will move in a circular path closely adjacent to wall 33. Additional magnetic means, which also may be an

exteriorly located permanent magnet 50, for cooperation with interior magnet 49 is affixed to a movable propelling member preferably the free end of a radially-offset arm 51 of driven shaft 52, which latter is rotatably mounted on an axis 5 coincident with the rotational axis of filling conduit member 27 in a bearing bracket 53 supported by and extending from standard 24b of supporting structure 24 beneath envelope 29. Magnet 50 is disposed with its upper face closely adjacent to wall 33 and substantially equidistant with magnet 49 from the common rotational axis, whereby, when both magnets are brought into close proximity to each other, rotation of driven shaft 52 will cause propelling member 51 to move in a path parallel to the row of sample receivers and thereby produce concurrent rotation of filling conduit member 27. Shaft 52 is driven by magnet drive shaft 54, which is also journaled in bearing bracket 53, through the medium of direction-change means such as beveled gears 55—56.

Magnet drive shaft 54 is diagrammatically represented in Figs. 4 to 8, inclusive, in operative cooperation with automatic means for intermittently rotating said shaft to move discharge spout 43 of filling conduit member 27 by step-by-step from one receiver holder 25 to the next one with suitable dwell periods in holder-registering positions to permit the drainage of distillate samples into the respective receivers.

Referring now to Fig. 4 in particular, the preferred form of electro-mechanical operating means for the sample cutter will now be described. Incidentally, this figure of drawing represents in broken lines the operating means in inoperative, shut-down condition following a completed major-cycle sample cutting run and requiring the closing of a re-setting electric switch, which has just occurred, before further operation can commence. The prime mover for the operating means is a constant-speed electric motor 57, which is connected with a source of current primarily through conductors 58—59. A main switch 60 controls the connection of power circuit 58—59 with the source.

Prime mover motor 57 causes rotation of a camshaft 61 in counter-clockwise direction at very slow speed through the medium of reduction gearing (not shown). In the illustrative example, it will be assumed that the speed is one revolution per minute. On camshaft 61 there are three cam wheels 62, 63 and 64, which respectively actuate electric switches 65, 66 and 67.

Each of the three switches 65—66—67 may be of any desired type, such as a micro-switch for example, but is conventionally represented in the drawings as comprising a stationary-contact member 68 and a movable contact member 69, which latter acts as a cam-follower in relation to its corresponding cam wheel. Spring 70 serves both to cause movable contact member 69 to follow its cam wheel and to open the switch.

Cam wheel 62 has a cam indentation 71 and a dwell surface 72 which extends throughout an arc of nearly 360 degrees. In the operational condition of the mechanism represented in Fig. 4, switch 65 is open and cam indentation 71 is in position to close said switch as soon as camshaft 61 commences to rotate. Thereafter, dwell surface 72 will keep switch 65 closed throughout a complete revolution of camshaft 61. Functionally, switch 65 is a maintainer switch.

Stationary contact member 68 and movable contact member 69 of switch 65 are connected

in series with the power circuit 58—59 for prime mover motor 57 by conductors 73 and 74, respectively. Specifically, conductors 73 and 74 bridge a gap in conductor 59 of said power circuit. The gap is further bridged by a mercury switch 75 which is energized periodically by a motor-starting timer 76 (Fig. 1). When energized, mercury switch 75 will permit current to flow across the gap. Timer 76 may be of any well known type which may be set to close the circuit of mercury switch 75 either at predetermined time intervals, or in response to changes in temperature or volume of the distillate in the distillation apparatus as registered by recording thermometric means or a liquid level gauge, respectively (not shown), operatively associated with said apparatus. We do not claim invention of anything new in the timer or in its specific operational relation to the distillation apparatus. Our invention lies in the periodic energization of the mercury switch in order to start prime mover motor 57 automatically in response to a predetermined condition which it is desired shall initiate each minor cycle of operation of the sample cutter which causes the drainage of each distinct distillate cut or fraction into one of the sample receivers and also causes subsequent advance of the filling conduit member into registration with the next succeeding sample receiver of the series. Closing of switch 65 serves to additionally close the gap in conductor 59 of the power circuit, which otherwise would be opened as soon as mercury switch 75 becomes de-energized at the end of the momentary starting impulse supplied thereto by timer 76. According to their operational functions, mercury switch 75 is the primary "starting switch" and switch 65 is the primary "maintainer switch."

Switch 66 is shown in open condition with its movable contact member riding on the dwell surface 77 of cam wheel 63. This dwell surface 77 extends through an arc of substantially 180 degrees in order to keep switch 66 open throughout approximately one-half revolution of camshaft 61. A cam face 78 of substantially 180 degrees of arc in extent intervenes between the ends of dwell surface 77 and is adapted to act upon movable contact member 69 in a manner to close switch 66 for the remaining one-half of the cyclic revolution of camshaft 61. Cam face 78 is represented in a position wherein it will become operatively engaged with movable contact member 69 of switch 66 as soon as camshaft 61 commences to rotate.

Switch 66 serves to control the electric circuit of the solenoid coil of drainage valve N of the distillation apparatus and may be termed the "drainage switch." To this end, stationary contact member 68 and movable contact member 69 are connected in parallel with power circuit 58—59 by conductors 79 and 80, respectively. Circuit 22 of drainage valve N is connected in series with conductor 79. When switch 66 is closed, valve N will be opened to permit drainage from collector H to the sample cutter 21 of a sample cut or fraction of the distillate in said collector. The volume of the cut will depend upon the closed condition time of switch 66 as determined by the length of cam face 78 and the speed of rotation of camshaft 61.

Cam wheel 64 has a cam nose 81 and a dwell surface 82 which extends through an arc of nearly 360 degrees. In the operational condition of the mechanism represented in Fig. 4, switch 61 is open and cam nose 81 has just cleared movable contact member 69 of said

switch at the end of a preceding revolution of camshaft 61. Switch 67 is therefore open and will be maintained open by dwell surface 82 throughout nearly 360 degrees of rotation of camshaft 61. Said switch 67 is connected in series with the starting power circuit 83 of the motor 84 which operates magnet drive shaft 54. Starting power circuit 83 is connected in parallel with main power circuit 58-59. When cam nose 81 of cam wheel 64 approaches the position shown in Fig. 4, which marks the end of a cyclic revolution of camshaft 61, switch 67 will be closed momentarily to start magnet drive motor 84. Switch 67 thus constitutes a starting switch only and may be termed the "secondary starting switch." Further operation of motor 84 is continued, until magnet drive shaft 54 has turned through a fraction of a revolution sufficient to advance discharge spout 43 of filling conduit member 27 one step from a filled sample receiver to the next succeeding empty one, through the action of an intermittent-feed cam wheel 85 affixed to said drive shaft. This feed cam wheel has plural, regularly spaced cam noses 86 with intervening dwell indentations 87 which are equal in number to the sample receiver holders 25 of sample cutter proper 21. Fewer than the actual number of indentations are shown in Figs. 4 to 8 due to the reduced scale employed.

A secondary maintainer switch 88 controls a secondary circuit 89-83 for magnet drive motor 84, which is also connected in parallel with main power circuit 58-59. Said switch 88 comprises stationary contact member 90 and movable contact member 91, which latter is urged by spring means 92 against the peripheral faces of intermittent-feed cam wheel 85. In the shut-down condition shown, feed cam wheel 85 is in mid-step position, wherein switch 88 is closed, in the broken line representation.

When starting operation of magnet drive motor 84 occurs, through the closing of starting switch 67, intermittent-feed cam wheel 85 will be moved counter-clockwise in partial rotation sufficiently before said starting switch is opened again to effect closing of maintainer switch 88 under conditions represented in subsequent views wherein said switch 88 is in open position. In this way, continued operation of motor 84 is assured just long enough to advance intermittent-feed cam wheel 85 one complete step. When movable contact member 91 of switch 88 has dropped into the next indentation 87 of intermittent-feed cam wheel 85, the said switch will open the secondary circuit of motor 84. Movable contact member 91 additionally cooperates with the indentations 87 of said cam wheel 85 to provide a pawl-and-ratchet action which offers sufficient resistance to motor 84 in its power-off condition to stop it instantly each time said movable contact member enters one of the indentations.

A second cam wheel 93 on magnet drive shaft 54 cooperates with an automatic shut-down switch 94 to open the main power circuit upon completion of a major cycle of the sample cutter when the trailing sample receiver of the series has received its distillate cut. Said cam wheel 93 has a cam indentation 95 and a dwell surface 96 which extends throughout an arc of nearly 360 degrees. In the operational condition of the mechanism represented in solid lines in Fig. 4, shut-down switch 94 is closed as a result of previous closing of a reset switch which will be described more fully presently. Stationary contact member 97 and spring-opened movable con-

tact member 98 of shut-down switch 94 are connected in series with main power circuit 58-59 by conductors 99 and 100, respectively.

- A manual re-set switch 101 bridges conductors 99 and 100. After main switch 60 has been closed prior to a sample cutting run, re-set switch 101 must be closed to start magnet drive motor 84 through energization of circuit 89—switch 88—circuit 83, and thereby effect completion of the advance of filling conduit member 27 from the trailing receiver holder 25 in the series to the leading one preliminary to the commencement of a new sample cutting run. This action is almost instantaneous and precedes any operation of prime mover motor 57. When completed, movable contact member 91 of switch 88 will have dropped into the next indentation 87 of intermittent-feed cam wheel 85 and said switch will have opened. At the same time, shut-down switch 94 will have been closed by movement of cam wheel 93. Dwell surface 96 of cam wheel 93 will thereafter maintain switch 94 closed throughout the remainder of the intermittent major cycle one revolution of drive shaft 54.
- During the major cycle of operation of the sample cutter, it is desired that distillate from the top of column A of the distillation apparatus shall be diverted into collector H at intervals in accordance with the time ratio established by a predetermined setting of timer T, whereas, upon termination of said major cycle, return of the distillation column A to a total reflux condition is imperative. These requirements have been met by providing a total reflux restoration switch 102 for actuation by a third cam wheel 103 on magnet drive shaft 54. Stationary contact member 104 and spring-opened movable contact member 105 are connected in series with conductors 20-20 of the circuit J of electromagnet I, which actuates swinging funnel E of the distillation apparatus and which is primarily controlled by timer T. When switch 102 is open, as shown in broken lines in Fig. 4, the circuit J will be open to permit swinging funnel E to assume its vertical total reflux position (not shown). Cam wheel 103 has a cam indentation 106 and a dwell surface 107 extending through an arc of nearly 360 degrees. In the operational condition represented in Fig. 4, cam indentation 106 has just closed switch 102. Thereafter, dwell surface 107 serves to keep switch 102 closed throughout the remainder of one revolution of shaft 54 or until the end of the complete major cycle of operation of the sample cutter.
- The operation of the preferred embodiment of the invention in cooperative combination with a reduced-pressure type distillation apparatus should be understood upon successive consideration of Figs. 1, 2, 4, 5, 6, 7 and 8.
- It will be assumed that the operator of the distillation apparatus has returned to the laboratory and found everything in the expected condition following completion of an overnight major cyclic run of the sample cutter. All of the receivers 26 contain their respective cuts of distillate and are still attached in fluid-tight relation to holders 25. Cam-actuated switches 65, 66, 67, 94 and 102 are open, but secondary maintainer switch 88 is closed. These positions of switches 88, 94 and 102 are represented in broken lines in Fig. 4 (and also in Fig. 8). The movable contact members of these switches have been foreshortened in order to illustrate more clearly their major cycle terminal positions, which are slightly different from the solid line positions in Fig. 4, which

represent the condition after reset switch 101 has been closed manually to operate magnet drive motor 84 just long enough to shift discharge spout 43 of filling conduit member 27 (Figs. 1 and 2) into registration with the holder to which the first sample receiver of a new series is to be attached. Since closing of reset switch 101 would have no effect on motor 84 if secondary maintainer switch 88 were not closed at the time, by displacing the cam indentations 87 of intermittent-feed cam wheel 85 angularly from cam indentations 95 and 106, respectively, of cam wheels 93 and 103, one dwell surface 86 of said cam wheel 85 will be pressing movable contact member 91 into circuit closing contact with stationary contact member 90 while movable contact members 98 and 105, respectively, of switches 94 and 102 are seated in circuit opening positions in cam indentations 95 and 106, respectively, of cam wheels 93 and 103 as represented in broken lines.

Before the liquid-containing receivers 26 can be detached from their respective holders 25 for replacement by a fresh series of empty receivers, it is necessary to close valve 23a and then open atmospheric vent valve 23b in order to preserve the vacuum condition in the distillation apparatus and to release the suction on the receivers. Valve N must be in closed condition, too, but that was effected automatically upon completion of the final minor cyclic closing operation of switch 66.

When the fresh series of empty sample receivers are in attached position and properly secured by devices 35, atmospheric vent valve 23b is closed and valve 23a is then opened. Now, reset switch 101 is closed momentarily to start magnet drive motor 84 and thereby turn cam wheels 85, 93 and 103 to the positions shown in solid lines in Fig. 4. It should now be realized why it is so essential that secondary starting switch 88 be closed prior to the manual closing of reset switch 101. Otherwise, the circuit 79-89-83 which connects magnet drive motor 84 in parallel with circuit 58-59-99-100 would be open. At the instant reset switch 101 is closed, circuit 20 will be closed (live condition shown by heavy lines) by reflux restoration switch 102 to make it possible for timer T of the distillation apparatus to commence its periodic operation of swinging funnel E through alternate energization and de-energization of electromagnet I at the predetermined time intervals. With the exception of circuit 20, all other local circuits represented in Fig. 4 are dead (light lines) and all movable parts of the mechanism are at a standstill.

Turning now to Fig. 5, it will be observed that the first stage of the first minor cycle of operation of the sample cutter has occurred. At this stage, timer 76 has energized the primary circuit of mercury starting switch 75 and this switch has closed the circuit 58-59-99-100-switch 94 (heavy lines) to start prime mover motor 57. Fig. 5 represents the condition at the instant motor 57 is about to start.

The energization period of primary starting switch 75, as established by timer 76, is sufficient to turn camshaft 61 counter-clockwise until primary maintainer switch 65 has become closed, as shown in Fig. 6, to continue operation of motor 57. Drainage control switch 66 also has been closed to effect the opening of solenoid valve N of the distillation apparatus and thereby start drainage of distillate from collector H down ex-

tension duct 22 to filling conduit member 27. This may be termed the "primary drainage stage." Throughout substantially half a revolution of camshaft 61, cam face 78 of cam wheel 63 will keep switch 66 closed. Thereafter, dwell surface 77 will permit switch 66 to open and remain in that position for substantially another half revolution to permit drainage of the cut sample on down through filling conduit member 27 into the sample receiver aligned with its discharge spout 43. This may be termed the "secondary drainage stage" and is represented nearly at the end of its progress in Fig. 7. This view also shows secondary starting switch 67 closed momentarily by cam nose 81 of cam wheel 64 to start magnet drive motor 84. Said motor 84 has turned counter-clockwise sufficiently to close secondary maintainer switch 88 and thereby continue the operation of said motor until filling conduit member 27 has been advanced one step from the filled receiver to the next empty receiver of the series.

Fig. 8 represents the condition of movable parts and switches when filling conduit member 27 has completed that step and marks the end of the first minor cycle of operation. It has been mentioned already that movable contact members 98 and 105 of switches 94 and 102, respectively, are shown by broken lines in the positions which will be assumed at the end of a major cycle. At that time, camshaft 54 will have completed one revolution and all sample receivers will have been subjected to the service of filling conduit member 27.

It will be observed in Figs. 4 through 8 that dwell surfaces 96 and 107 of cam wheels 93 and 103, respectively, serve to keep shut-down switch 94 and reflux restoration switch 102 closed throughout the entire major cycle. When shut-down switch 94 has been opened automatically at the end of the major cycle, the circuits of motors 57 and 84 will be interrupted until reset switch 101 is again manually closed to bring about the operational stage of Fig. 4. The complete major cycle incidental to one revolution of camshaft 54 requires as many minor cycles incidental to revolutions of camshaft 61 as there are sample receivers in the series (sixteen in the illustrative example).

Sometimes it becomes necessary to take one or more sample cuts independently of a cyclic series run, either at a different time or during such a run but aperiodic in relation to the regular cuts of the major cycle. To meet this requirement, manual switches 200 and 300, respectively, have been provided in circuit 83-83 in parallel relation to secondary starting switch 67 and in circuit 79-80 in parallel relation to switch 66. Momentary manual closing of switch 200 will start magnet drive motor 84 and, with the cooperation of secondary maintainer switch 88, continue operation of said motor until filling conduit member 27 has been shifted into registration with an empty sample receiver in the applied series. Then, closing of switch 300 for an appropriate length of time will cause drainage of the desired volume of distillate into the selected receiver. If this be done after termination of a minor cycle but before the next periodic energization of the operating circuit of motor 57, the irregular cut or cuts may be taken without affecting continuity of the major cycle. Because of the usual elapse of several minutes between minor cycles, the interposition of casual sample cuts is entirely practicable. If the re-

ceivers which contain the casual cuts are to be removed at once for immediate test purposes, valves 23a and 23b must be manipulated in the previously described manner before and after substitution of empty receivers for those which contain the casual cuts. The purpose of the substituted empty receivers is to seal the holders to which the receivers which were removed were attached. If the individual holders are provided with cut-off valves in accordance with the modification disclosed in Fig. 3, all that will be necessary is to close the cut-off valves of the affected holders.

Figs. 9 to 11 illustrate a modified form of sample cutter which is adapted for use with distillation apparatus that operates on the atmospheric distillation principle, or in connection with any apparatus which does not require sealing of the filling conduit member of the sample cutter from the atmosphere during delivery of sample cuts to the receivers. The modified sample cutter is very much more simplified than the preferred form illustrated in Figs. 1 and 2, and is better suited to the cutting of samples of granular or pulverulent solid materials.

In this instance, supporting structure 24 supports a unitary receiver holder assembly 108, which is in the form of a hollow annular body having individual holder sockets 109 in its top wall and is well adapted for utilization as a heat-exchange tank whenever it is desired to modify the temperature of the samples delivered to sample receivers 110 mounted in said sockets. As usual, sockets 109 are arranged in a circular row. Each sample receiver 110 has an enlarged mouth 110' which may rest upon the marginal edge of the holder socket in which it is inserted. (Fig. 10.) Enlarged mouth 110' also serves as a manipulating portion which may be engaged by the operator's fingertips to facilitate withdrawal from the socket. Furthermore, the mouth 110' presents a seat for a preferably spherical sealing closure member 111 associated with each holder socket 109. (Figs. 9 and 11.)

Holder assembly tank 108 is intended to contain a heating or cooling fluid agent, which may be supplied through bottom inlet 112 and discharged through elevated outlet 113 which determines the surface level in the case of liquid agents. In use, sample receivers 110 will be immersed in the fluid agent so that the desired heating or chilling of their contents may take place.

The filling conduit member 114 differs slightly from that shown in Figs. 1 and 2. Instead of having rotational pintles, the portion 115 located between funnel-shaped mouth 116 and radially offset discharge spout 117 is vertically disposed for engagement by an adjustable clamp 118 provided at the top of an extension piece 119 of driven shaft 52 of transmission mechanism 28. Said transmission mechanism is the same as in the preferred embodiment of sample cutter, but driven shaft 52 is modified to provide for detachable connection of its upper end with extension piece 119. For convenience in permitting quick detachment of extension piece 119 while producing concurrent rotation of said extension piece and driven shaft 52, the former has been provided with a terminal non-circular socket 120 for reception of the correspondingly shaped lower end 121 of the latter. In assembled position on extension piece 119, the vertical portion 115 of filling conduit member 114 will be centrally disposed in relation to the circular row of receiver

holder sockets 110 and discharge spout 117 will be positioned to follow a circular path of movement overlying said holder socket row for sequential registration with the respective sample receivers 110.

The spherical closure members 111 for the respective sample receivers are mounted to roll on track members 122, which are laid on the top wall of holder assembly tank 108 in horizontal alignment with the respective holder sockets 109. The track rails 122'-122' of track members 122 are inclined downward toward the corresponding holder sockets 109 and have laterally aligned check notches 122"-122" which are intended to seat the respective closure members 111 in idle, inoperative positions spaced to the mouths 110' of receivers 110 when mounted in holder sockets 109. The closure members 111 will thus be checked or restrained in their idle positions until pushed forcibly out of notches 122"-122" in the direction of the corresponding holder sockets 109, whereupon they will roll outward and drop into seated closing relation to the mouths 110' of sample receivers 110.

Convenient means for propelling closure members 111 from their check seats along the tracks into seated relation to the receiver mouths, one at a time as filling conduit member 114 is advanced step-by-step along the row of receivers, is the propelling arm 123 that projects radially from extension piece 119. This arm 123 is disposed in following relation to discharge spout 117 of filling conduit member 114 (considering the direction of rotation of the latter) and is just long enough and high enough to engage and sweep the spherical closure member 111 associated with each holder socket 109 from its restraining track notches 122"-122" down the track into seated relation to the receiver 110 mounted in said holder socket during the forward advance of said filling conduit member to the next receiver of the series.

An upright finger 124 is provided on propelling arm 123 for contact with the rear side of filling conduit member 114 to serve as positive means for driving the latter in its circular path of movement. Clamp 118 could be tightened sufficiently to insure effective driving of filling conduit member 114, but it is desirable to maintain that degree of frictional engagement between said clamp and filling conduit member which will permit the latter to yield instead of becoming broken in the event that discharge spout 117 thereof encounters an immovable obstruction in its path. For instance, back-lash in the power transmission mechanism 28 might cause retrograde movement of spout 117 into collision with a closure member 111 which has just been firmly seated in the path of movement of said spout.

The modified form of sample cutter disclosed in Figs. 9, 10 and 11 is operated by the electro-mechanical means illustrated in Figs. 4 to 8, inclusive, in the same manner as the preferred embodiment shown in Figs. 1 and 2. In this instance, sealing of the sample receivers is accomplished by means of spherical closure members 111 individually in succession as the former receive their cuts and filling conduit member 114 moves on its step-by-step travel, instead of collectively during the entire period of the major cycle as effected by envelope 29 under the influence of vacuum in the preferred embodiment disclosed in Figs. 1 and 2.

Having thus described the invention, we claim:

1. In a sample cutter of the class described,

a sealing envelope of non-magnetic material having communication with a vacuum line, plural sample receivers arranged in a horizontal row with upwardly open mouths, receiver holder means to support each sample receiver in communication with the interior of said envelope and in sealed relation to the outside atmosphere, a filling conduit member enclosed entirely within said envelope and having an intake mouth and a discharge spout, means also entirely enclosed within said envelope for movably mounting said filling conduit member in a manner to cause the spout thereof to travel along a path overlying the row of receiver mouths, a drainage duct penetrating said envelope in hermetically sealed joint therewith and having its inner end in registration with the intake mouth of the filling conduit member to deliver sequential cuts of material into the same, and means to operate the filling conduit member in its path of movement from one receiver to another in succession in such a manner that the vacuum condition within the envelope is preserved throughout the receiver filling operation, said operating means comprising a propelling member movable outside the envelope in a path parallel to the row of sample receivers, and mutually attracting magnetic means affixed to the filling conduit member and the propelling member respectively in such proximity to the intervening envelope wall that movement of the propelling member will produce concurrent movement of the filling conduit member in a manner to cause its discharge spout to follow the row of sample receivers.

2. A device for cutting periodic test samples from a distillation apparatus having a distillation column, a collector, a duct leading from said distillation column to said collector, adjustable flow diversion means movable between operative and inoperative positions and adapted when in operative position to divert reflowing distillate from the upper portion of said distillation column through said duct into the collector and when in inoperative position to permit total reflux of distillate within said column, a timer device to shift said flow diversion means from one of said positions to the other, a drainage duct leading from said collector, and valve means controlling said drainage duct, said sample cutting device comprising: plural sample receivers, receiver holder means adapted to support said sample receivers in a row for sequential introduction of distillate cuts; a filling conduit member having its open upper end underlying the drainage duct of said distillation apparatus and having a discharge spout arranged to overlie the row of receivers; power means for producing relative motion between said receiver holder means and said filling conduit member in a manner to move the discharge spout of the latter along the row of receivers; intermittent feed means for interrupting said relative motion for a predetermined drainage period upon registration of the filling conduit member discharge spout with each sample receiver in sequential order; and means responsive to movement of the filling conduit member to actuate the timer device in a manner to render the distillate diversion means of the distillation apparatus inoperative and thereby restore said distillation apparatus to total reflux condition upon registration of the discharge spout of the filling conduit member with the last sample receiver of the series.

3. A sample cutting device as defined in claim

2, wherein means is provided to open the drainage duct control valve means during said drainage period.

4: An automatic device for cutting sequential samples from a moving or stationary body of liquid or solid material located in the containing vessel of an associated apparatus having a drainage duct controlled by valve means, said sample cutting device comprising: a series of sample receivers; receiver holder means supporting said sample receivers in a circular row; a filling conduit member rotatably mounted on an axis concentric to the row of receivers and having its open upper end underlying the drainage duct of the associated apparatus and having a discharge spout arranged to traverse a circular path overlying the row of receivers; a drive shaft adapted to make one major cyclic revolution during progress of the filling conduit member along the complete series of receivers; power transmission means connecting the drive shaft with the filling conduit member; a second shaft adapted to make one minor cyclic revolution incident to registration of the filling conduit member with each receiver of the series; a prime mover to rotate said second shaft at constant speed; primary starting means for commencing operation of the prime mover at predetermined intervals corresponding in number to the receivers in the series; primary maintainer means for continuing operation of the prime mover for one complete revolution of said second shaft; means operable by said second shaft for opening the control valve means of the drainage duct for a predetermined period; power means for rotating the drive shaft; secondary starting means operable by said second shaft to start rotation of the drive shaft following completion of said drainage period; secondary maintainer means for continuing operation of the drive shaft; stopping means for the prime mover operable following actuation of the secondary maintainer means; intermittent feed means for interrupting operation of the drive shaft upon arrival of the filling conduit member discharge spout in registration with each sample receiver of the series; and shut-down means operable automatically to suspend operation of said prime mover at the end of the major cyclic revolution of the drive shaft.

5. An automatic sample cutting device as defined in claim 4, wherein manually operable reset means is provided for restoring the operative condition of the primary starting means to commence a new major cycle.

6. An automatic sample cutting device as defined in claim 4, wherein manually operable means is provided for independent operation of power means for the drive shaft and the means for operating the drainage duct control valve means, whereby a casual cut may be delivered to a selected receiver out of the regular sequential order.

7. An automatic device for cutting sequential samples from a moving or stationary body of liquid or solid material located in the containing vessel of an associated apparatus having a drainage duct controlled by electrical valve means, said sample cutting device comprising: a series of sample receivers; receiver holder means supporting said sample receivers in a circular row; a filling conduit member rotatably mounted on an axis concentric to the row of receivers and having its open upper end underlying the drainage duct of the associated apparatus and having a discharge spout arranged to traverse a cir-

cular path overlying the row of receivers; a drive shaft adapted to make one major cyclic revolution during progress of the filling conduit member along the complete series of receivers; power transmission means connecting the drive shaft with the filling conduit member; a cam-shaft adapted to make one minor cyclic revolution incident to the registration of the filling conduit member discharge spout with each receiver of the series; a main electric power circuit; a prime mover motor to rotate said camshaft at constant speed; a primary starting switch adapted when closed to connect said prime mover motor with said main power circuit; means for automatically closing said primary starting switch momentarily at predetermined intervals; a primary maintainer switch adapted when closed to continue the connection of the prime mover motor with the main power circuit; cam means operated by said camshaft for closing the primary maintainer switch when said camshaft commences to turn and for maintaining said switch closed until the end of each minor cyclic revolution of the camshaft; an electric circuit for said electric drainage duct valve of the associated apparatus, said circuit being connected in parallel to said main power circuit; a switch for said valve circuit; cam means operated by said camshaft to close said valve circuit switch during part of each minor cyclic revolution of the camshaft; an electric motor to operate the drive shaft at constant speed; a starting operating electric circuit for said drive shaft motor connected in parallel with the main power circuit; a secondary starting switch for said starting circuit; cam means operated by said cam-shaft to close said secondary starting switch at the end of each minor cyclic revolution of said camshaft; a maintainer electric circuit for said drive shaft motor connected in parallel to the main power circuit; a secondary maintainer switch in said maintainer circuit; intermittent-feed cam means operated by said drive shaft and adapted to close the secondary maintainer switch momentarily each time the drive shaft motor starts to rotate to permit partial rotation of said drive shaft sufficient to move the filling conduit member discharge spout from any sample receiver to the next one in the receiver series; a shut-down switch connected in series with the main power circuit; cam means operated by the drive shaft for opening said shut-down switch at the end of each major cyclic revolution of said drive shaft to suspend all operation of the sample cutting device, said shut-down switch cam means being adapted to maintain said shut-down switch closed throughout the remaining major portion of each complete major cyclic revolution of said drive shaft; the relative arrangement of the intermittent-feed cam means and the shut-down

switch cam means being such that the secondary maintainer switch will be closed when the shut-down switch is open; and a manual reset switch connected in series with the main power circuit and in short-circuiting relation to the shut-down switch to permit manual advance of the filling conduit member from the last sample receiver of the receiver series to the leading receiver thereof and also to render the sample cutting device operative again by closing the shut-down switch.

8. A sample cutter as defined in claim 1, said row of sample receivers being circular in arrangement, and bearing means located entirely within 15 the sealing envelope in sealed relation to the outside atmosphere for mounting the filling conduit member for rotation on a vertical axis concentric to the row of sample receivers.

9. A sample cutter as defined in claim 8, said sealing envelope having a side wall of circular horizontal cross-section and an upthrust bottom wall of exteriorly concave form providing an external central concavity and an internal annular channel between said bottom and side 25 walls; the sample receivers being supported with their mouths in communication with said annular channel; the discharge spout of the filling conduit member being mounted to travel through said annular channel; the propelling member 30 being disposed within the external concavity of the bottom wall of the sealing envelope and mounted for rotation on a vertical axis coincident with that of the filling conduit member; and the magnetic means of the filling conduit member being carried by the discharge spout thereof 35 through said annular channel.
